(57) **CLAIM**

The ornamental design for a front handle for a vacuum cleaner, as shown and described.

DESCRIPTION

FIG. 1 is a perspective view of a front handle for a vacuum cleaner showing our new design;

FIG. 2 is a front elevational view thereof;

FIG. 3 is a left side elevational view thereof;

FIG. 4 is a top plan view thereof; and,

FIG. 5 is a right side elevational view thereof.

The parts shown in broken lines in FIGS. 1-4 are shown for illustrative purposes only and form no part of the claimed design.
